UNITED STATES PATENT OFFICE.

TOBIAS E. RAFFEL, OF NEW YORK, N. Y., ASSIGNEE TO PAPER WORKING MACHINES CO., A CORPORATION OF NEW YORK.

TUBE-MACHINE.

1,103,378.

Specification of Letters Patent. Patented July 14, 1914.

Application filed May 4, 1912. Serial No. 695,273.

To all whom it may concern:

Be it known that I, TOBIAS E. RAFFEL, a citizen of the United States, and a resident of the city, county, and State of New York, have invented certain new and useful Improvements in Tube-Machines, of which the following is a full, clear, and exact specification.

My invention relates to a machine, employing one or more suitably supported presser belts, which is adapted to wind a plurality of strips of paper spirally around a mandrel, and unite them to form a continuous tube.

The object of this invention is to increase the efficiency and capacity of a machine of the type mentioned, by providing means whereby it may be readily adjusted for the manufacture of tubes of various diameters and thicknesses. The diameter of the tube to be formed is dependent upon the diameter of the mandrel upon which it is made, as well as the width of the strips forming it. In order, therefore, that my improved machine may be operated with mandrels of different diameters, I provide means for supporting and holding the mandrel, which means are readily adjusted to the size of the particular mandrel used. When the mandrel is changed for one of a different size, the distance between the two belt-carrying pulleys must be altered to slacken or tighten the belt so as to accommodate it to the increased or decreased diameter of the mandrel, as the case may be. Heretofore this has been accomplished by having one of the pulleys movable and adjusting its position with respect to its companion fixed pulley; consequently, when mandrels of increased diameter are employed, the movable pulley is moved toward the mandrel, thereby shifting the position of contact between the belt and the mandrel closer to the pulley. This action decreases the efficiency of the belt in performing its function of feeding and pressing the strips and limits the capacity of the machine to operation with mandrels of a comparatively narrow range of differences in sizes.

In my machine, I obviate the disadvantages just mentioned by having both of the belt carrying pulleys movable and providing means whereby they may be simultaneously moved toward and away from each other. In this manner I am enabled to maintain the tension on the belt in the center thereof,

irrespective of the diameter of the particular mandrel used in connection therewith.

A further advantage of my improved construction consists in having each of the base pieces carrying the belts mounted on a separate carriage which is arranged for independent longitudinal movement on the bed of the machine. By moving the carriages, the presser belts carried thereon may be readily shifted on the bed of the machine to any desired position for the manufacture of tubes of various thicknesses. For example, one of the belts may be located at one end of the bed close to the mandrel support, while the other belt may be located at the extreme opposite end thereof, which adjustment affords ample room for feeding a large number of strips on to the mandrel in the space between the two belts so as to permit of the construction of a tube of any desired thickness.

I attain the objects of my invention by means of the construction and arrangement of parts shown in the accompanying drawings forming part of this specification, in which—

Figure 1 is a plan view of my machine; Fig. 2 is a longitudinal section thereof; Fig. 3 is a transverse section, and Fig. 4 is a detailed view showing the connection between the carriage and the slidable power transmission gear.

(1) represents the bed of the machine having two spaced ways (2) upon which are mounted, for longitudinal movement, the carriages (3). At one end of the bed is mounted a standard comprising two upright arms (4) to which are securely fastened the chucks (5), located in parallel vertical planes and having their centers in line with each other. The chucks are provided with adjustable jaws (6) which are adapted to be opened or closed by turning the face plate of the chuck so as to accommodate the said jaws to the size of the particular mandrel used. A mandrel (7) is firmly held in the jaws of the two chucks and extends beyond them lengthwise of the bed of the machine and substantially parallel to the center line thereof. By reason of this construction the mandrel will be securely and rigidly supported in the machine and the machine will be adapted to receive and be operable with mandrels of a great variety of sizes.

A power shaft (8) having a power pulley (9) at one end thereof is supported in suit-

able bearings (10) and extends longitudinally and centrally through the interior of the bed (1). The bevel gears (11) are keyed in a slot on the shaft (8) so that they may slide lengthwise on the shaft and are provided with grooves (12) in which are engaged the yoke pieces (13) rigidly fastened to the carriages (3) and dependent therefrom.

10 A base piece (14) extending cross-wise of the bed of the machine is mounted on each carriage (3) so as to swing freely around the spindles (15) as a center. The lower ends of the spindles carry the bevel gears (16) which mesh with the gears (11) and the upper ends carry the bevel gears (17) meshing with the gears (18) rigidly secured to the shafts (19).

At each end of the base pieces (14) is carried a slidable supporting member (20) provided with two horizontal arms (21) between which is carried a pulley (22) having a vertical shaft (23) journaled in said arms and extending downwardly through the lower one. The lower ends of the shafts (23) carry the bevel gears (24) in mesh with the bevel gears (25) which are keyed to slide lengthwise (with their respective supporting members) on the shafts (19).

30 Each pair of pulleys (22) carries a belt (26) which is arranged with one run thereof wound around the mandrel (7). Power is constantly being transmitted to the pulleys so as to turn the belts by means of the power shaft (8), secondary shafts (19) and their intermeshing gears.

The slidable members (20) are provided with internally threaded sleeves (27) projecting therefrom, which sleeves work on the threads of the right and left screws (28). The latter are supported in suitable bearings (29) and are furnished with handle levers (30) whereby the screws may be turned so as to simultaneously move the supporting members (20) toward or away from each other on their respective base pieces.

(31) represents a suitable device of any well known type for adjusting the angular relation of the base pieces (14) and the belts carried thereby, with the mandrel.

The two base pieces are connected together by an adjustable link (32) so that while each separate base piece may be independently moved lengthwise on the bed, they may be arranged to swing together.

From the foregoing description it will be apparent that the various adjustments of the parts of the machine may be effected 60 without interfering with the continuous transmission of power to the belt carrying pulleys.

The operation of the type of machine to which my invention relates will be fully understood by those skilled in the art, and it is believed, therefore, that it is unnecessary for the purpose of this specification, to give a detailed description of the operation thereof.

What I claim is:

1. In a tube machine, in combination with a mandrel; a bed; a mandrel support carried on said bed, adapted for adjustment to mandrels of different diameters; two presser belts; two separate base members, each mounted on the bed for independent movement lengthwise thereof; a pair of pulleys for each belt carried on each base member, and arranged for adjustment equally toward and away from each other thereon, and means for transmitting motion to both belts.

2. In a machine for making spiral tubes, the combination of a mandrel, a bed, a carriage movable thereon, a base piece centrally pivoted on the carriage, a belt, pulleys therefor, supports for the pulleys slidably mounted on the base piece, means for simultaneously adjusting both supports to vary the distance between them, a driving shaft extending through the bed, and operative connections for transmitting motion from the driving shaft to the pulleys.

3. In a machine for making spiral tubes, the combination with a mandrel of a swingable base piece, two pulley supports slidably mounted thereon, pulleys in said supports, a belt carried on the pulleys, a driving shaft disposed under the base piece midway between the pulley supports, operative connections for transmitting motion from the driving shaft to the pulleys, and means for moving both pulley supports equally toward or away from each other.

4. In a machine for making spiral tubes, the combination of a mandrel, a bed, two carriages movable thereon, a base piece centrally pivoted on each carriage, two belts, pulleys for said belts, supports for the pulleys slidably mounted on each of the base pieces, a driving shaft extending centrally through the bed, operative connections for transmitting motion from the driving shaft to the pulleys, and means for swinging the base pieces to adjust the angle of the belts in respect to the mandrel.

In testimony whereof I have hereunto signed my name in the presence of two subscribing witnesses.

TOBIAS E. RAFFEL.
